UNITED STATES PATENT OFFICE.

FRANK D. SCHLEICHER, OF MIFFLINTOWN, PENNSYLVANIA.

BROOM.

1,278,227.

Specification of Letters Patent. Patented Sept. 10, 1918.

Application filed February 19, 1917. Serial No. 149,466.

To all whom it may concern:

Be it known that I, FRANK D. SCHLEICHER, a citizen of the United States, residing at Mifflintown, in the county of Juniata and State of Pennsylvania, have invented a certain new and useful Improvement in Brooms, of which the following is a specification.

The present invention relates to an improved broom construction and has for an object, generally, to provide a broom wherein the broom-head or brush-part can be removed from the handle after it has been worn out and replaced by a new broom-head so that the entire device is ready for use as a broom or brush as in its original condition and the parts can be readily assembled or disassembled by anyone.

A further object of the invention is to provide a holder for the broom-head which coöperates with the broom-corn of the head to hold the brush fibers firmly clamped in use and wherein the holder is clamped or firmly fixed in a positive manner at a point 25 or line some distance from the handle end of the broom-head. A further object is to provide means upon the broom-head which are adapted to coöperate with means upon the holder to prevent the broom-head from 30 pulling out of the holder when the broom is in use.

A still further object of the invention is to provide a handle attaching means for a broom-head in which the handle, while 35 movably secured to the holder, has a positive connection with the broom-head so that there is no possibility of the handle moving laterally with respect to the brush-head and thus placing the strain under the sweeping 40 operation upon the points of attachment between the handle and the holder.

For the purpose of illustrating my invention, I have shown in the accompanying drawings one form thereof which is at present preferred by me, since the same has been found in practice to give satisfactorily and reliable results, although it is to be understood that the various instrumentalities of which my invention consists can be variously arranged and organized and that my invention is not limited to the precise ar-

rangement and organization of the instrumentalities as herein shown and described.

Referring to the drawings:

Figure 1 represents a side elevation of a 55 broom embodying my invention;

Fig. 2 represents an edge elevation of the same;

Fig. 3 represents on an enlarged scale an 60 edge elevation of the holder-parts;

Fig. 4 represents a side elevation of the broom-head;

Fig. 5 represents a section on line 5—5 of Fig. 1;

Fig. 6 represents a detail of the holder 65 connection;

Fig. 7 represents a detail of the coupling part of the handle;

Fig. 8 represents a detail of a coupling 70 part employed with the brush-head.

1 designates the broom-head proper and which in the present instance is formed of broom-corn sewed in the usual manner as indicated at 2 but provided with a plurality of binding wires 3 adjacent the handle end of 75 the same and by which relative movement between the broom-head 1 and the holder 4 is prevented. The wires 3, as here shown, are preferably of relatively large diameter and formed of round stock in cross-section 80 and are adapted to seat within corresponding grooves 5 formed in the parts of the holder 4. The holder 4 is preferably made of sheet metal pressed to the required shape and there are two parts each of which 85 closely approximates the contour of an end portion of the broom-head so that when the aforesaid parts are assembled, as shown in Fig. 2, the butt end of the broom head fits snugly within the holder without placing 90 such a gripping action upon the fibers as to cause them to wear quickly and break at the line of connection with the holder. One of the parts of the holder 4 is provided with an off-set 6 at each side which are suitably 95 cut away to form slots 7 respectively for the reception of ears 8 formed integral with the other part of the holder. Thus in assembling the holder the two off-sets 6 are located, respectively, at the edges of the 100 broom-head and in such alignment with the tongues 8 of the opposite holder part, that

the said ears or tongues inter-engage the slotted off-sets and form a positive connection to maintain the holder in fixed engagement with the broom-head as required. Furthermore, since the ears 8 and slotted portion 7 are curved and substantially concentric, the connection is that of a pivot which permits one part to swing away from another without becoming detached therefrom. The opposite end of the holder part is provided with a thread 9, which, when the two parts are brought together into operative position, forms a continuous cylindrical threaded portion adapted to fit into and be held by the threaded socket 10 which is pinned as shown at 11 or otherwise secured in a fixed manner to the broom-handle 12.

Referring to the handle 12, it will be noted that it is provided with a pointed end 13 which extends sufficiently from the coupling socket 10 to enter the broom-corn when the device is assembled, and as a suitable means to receive and hold this end 13, I have preferred to employ a bushing 14 which is driven into the broom-head at substantially the middle portion of the top edge and juxtaposed with respect to the end of the handle. This bushing 14 is suitably bored to form a tapered opening and the walls of this opening are threaded as shown at 16 to receive the threaded portion of the broom end 13 and the pitch of the thread of the bushing 14 and handle end 13 is the same as the pitch of the holder-parts 9 and coupling 10, so that the handle may be screwed into both parts simultaneously as will be understood. In connection with the bushing part 14 it will be noted that it has a flanged head 17 thereon provided with teeth 18 which are adapted to be embedded into the broom-head and to securely anchor the part in place.

It is believed that the assembling of the device will be readily understood from the foregoing description and therefore it is deemed unnecessary to give a detailed explanation of the operation of the device, though attention is called particularly to the fact that the construction is such that the holder is positively held at both ends so that under the sweeping action while the broom is in use, any tendency of the holder to open and release the broom-head or become detached from the handle is effectually prevented. Thus, in one instance, the two ends which together form a cylindrical part to be coupled are adapted to pass within the socket 10 which when screwed down to its normal holding position encompasses the holder ends and they cannot separate. On the other end, the pivots of the holder parts form a positive holding means which resists any opening tendency. Furthermore, the provision of the binding wires 3, as outstanding elements on the broom-head and

which seat within the grooves 5, gives a 65 construction which prevents the holder from moving longitudinally of the brush-head and causes the parts to be held in a substantially permanent manner.

I am aware that it has heretofore been 70 proposed to employ holders in which the brush-head or stub can be replaced when it is worn out, but in practice, it has been found that such devices are impractical because of the fact that there has been no adequate means for connecting the handle to the holder and the holder to the broom-head so as to compensate for the strains which devices of this character are subject to in use. It has been found in such devices 75 that the handles soon become detached from the holder-part, the holder-parts themselves are easily broken and disconnected from the other adjuncts and where wires, bolts or the like are passed through the brush fibers, the 80 latter are soon cut and worn so that the entire device becomes useless. By my present invention, I have overcome the foregoing disadvantages and have accomplished, with 85 few parts easily assembled, that which others 90 have failed to do.

It will now be apparent that I have devised a novel and useful construction which embodies the features of advantage enumerated as desirable in the statement of the invention and the above description and while I have in the present instance shown and described the preferred embodiment thereof which has been found in practice to give 95 satisfactory and reliable results, it is to be understood that the same is susceptible of modification in various particulars without departing from the fair spirit or scope of the invention or sacrificing any of its advantages.

What I claim is:

1. In a device of the character stated, the combination of a broom-head provided with a plurality of binding wires adjacent one end, said wires projecting laterally about the circumference of the broom-head, a holder comprising two parts each part having grooves therein to form seats to receive the respective binding wires, means to pivotally connect the holder-parts below the upper edge of the broom-head, said parts being provided with a threaded end portion, a handle having a threaded tapered end, a bushing provided with a threaded opening to receive said handle end, said bushing being secured to said broom-head and means to removably connect said handle and holder.

2. In a device of the character stated, the combination of a broom-head provided with transversely arranged rows of stitching, a plurality of binding wires between said stitching and one end of the broom-head,

said wires forming continuous lateral offsets projecting beyond the respective planes of the sides of the broom-head, a two-part holder provided with complementary grooves adapted respectively to seat upon said offsets to form interlocking connections to prevent relative movement between said holder

and said broom-head, means to pivotally connect the holder parts, a handle and means to removably connect said holder and said handle.

In testimony whereof, I have hereunto signed my name.

FRANK D. SCHLEICHER.
